UNITED STATES PATENT OFFICE.

FRED H. ARNOLD, OF NEW HAVEN, CONNECTICUT.

DESIGN FOR A VETERAN'S-GRAVE DESIGNATOR.

SPECIFICATION forming part of Design No. 18,517, dated August 14, 1888.

Application filed May 22, 1888. Serial No. 274,701. Term of patent 14 years.

To all whom it may concern:

Be it known that I, FRED H. ARNOLD, a citizen of the United States, residing at New Haven, in the county of New Haven and State 5 of Connecticut, have invented and produced a new and original Design for a Veteran's-Grave Designator, of which the following is a specification, reference being had to the accompanying drawing, in which the only figure is 10 a front elevation of my newly-designed veteran's-grave designator.

A designates the ground or backing, at the lower part of which the principal ornament is the representation of a wreath, *a a*. Below 15 the central portion of the wreath is a raised figure, *b*, in the representation of two muskets crossing each other, as shown. Above the central portion of the wreath is another figure, *c*, representing two swords crossing each 20 other, and above the swords are any desired figures or characters—as, for instance, '61-

'65, representing the years of the war. Across the emblem, above the entire wreath, is a bar, *B*, with any desired letters or word thereon—as, for instance, the word "Veteran"—and 25 the two ends of a battle-ax, *d*, are shown at the ends of the bar *B*. Above the bar *B* is the representation of two Union flags, *ff*, with their staffs slanting upward and outward. Crossing the flags' staffs are two cannons, *g g*. 30 Surmounting the whole is a representation of an American eagle, *C*, as shown.

I claim—

The design for a veteran's-grave designator herein shown and described, the same consisting of the body *A*, having thereon the representation of the musket, wreath, swords, flags, cannon, eagle, battle-ax, and bar *B*. 35

FRED H. ARNOLD.

Witnesses:

JAMES SHEPARD,
C. A. SHEPARD.
